UNITED STATES PATENT OFFICE.

DANA E. HEMPHILL, OF SALT LAKE CITY, UTAH.

CHAIN-CLASP OR SAFETY-CATCH.

1,089,340.

Specification of Letters Patent. Patented Mar. 3, 1914.

Application filed December 2, 1912. Serial No. 734,602.

To all whom it may concern:

Be it known that I, DANA E. HEMPHILL, a citizen of the United States, residing at Salt Lake City, in the county of Salt Lake and State of Utah, have invented certain new and useful Improvements in Chain-Clasps or Safety-Catches; and I do declare the following to be a full, clear, and exact description of the invention, such as will enable others skilled in the art to which it appertains to make and use the same.

This invention relates to improvements in clasps or safety catches and more especially to clasps for connecting a chain to a garment.

One object of the invention is to provide a simply constructed self locking clutch fastener for reliably securing a pin or other ornament to a garment and which cannot be accidentally opened by a pull exerted either on the ornament or on the fabric to which it is attached.

With this and other objects in view, the invention consists of certain novel features of construction, and the combination and arrangement of parts as will be more fully described and claimed.

In the accompanying drawings; Figure 1 represents a front elevation of this improved clasp applied as a fastening element for securing a man's watch chain to his vest, a portion only of the latter being shown; Fig. 2 is a longitudinal section taken on the line 2—2 of Fig. 1 with the parts in operative position; Fig. 3 is a similar view of the clasp in open position and with parts broken out; Fig. 4 is a bottom plan view of the clasp shown closed in full lines and open in dotted lines; Fig. 5 is a detail perspective view of the penetrating hook or prongs; Fig. 6 is a similar view of one of the locking members.

In the embodiment illustrated the invention is shown applied to a clasp for securing a watch chain to a man's vest or coat being designed as a substitute for the ordinary cross bar used for this purpose which is passed through the button hole of the garment. This clasp comprises a face plate 1 which may be plain or ornamented and which has a hollow rear face to which is secured a plate 2 housed therein. A hook 3 is pivotally mounted on one end of the plate 2 and, as shown, consists of a head 4 having a bore 5 extending longitudinally thereof to form a journal for a connecting pintle 6

which is mounted in suitable bearings on the plate 2. Extending laterally from said head 4 are spaced inwardly curved penetrating prongs as 7 spaced apart at their base sufficiently to receive a link 8 which is pivotally mounted between them, the end through which the pivot passes being offset as shown at 9 to position the link when applied close to the outer face of the plate 2 and in substantially parallel relation thereto and this offset pivoted end also permits the pronged head 4 to open and close without exerting undue strain on said link, the free end of which is pivotally connected with one end of a bell crank lever 10 which is fulcrumed to the base plate 2 in longitudinal alinement with the center of said head 4 where the link 8 is connected. This lever has one short arm 11 to the free end of which the free end of the link 8 is pivoted. The long arm 12 of the bell crank lever 10 extends over the edge of the front plate 1 and the free end thereof is offset as shown at 13 to permit it to extend over the inclined edge of the front or facing plate. The free end of the lever arm 12 is preferably beveled and extends beyond the edge of the plate 1 a sufficient distance to permit it to be engaged when in any position for actuating it and when closed to lock the hook in operative engagement with the fabric. The beveled end 14 when closed extends flush with the edge of the front plate 1 and thus avoids all danger of said end becoming engaged accidentally with adjacent objects, whereby it would be likely to be opened and the object of the device defeated. The curvature of the prongs 7 may be varied to adapt the device to be applied to thicker or thinner fabric as may be desired, the curvature being greater when it is used on thick material. An eye 15 is shown fixed to the end of the plate 2 opposite that to which the hook 3 is secured and is designed to receive a link of a chain C which is to be secured, it being understood that any other article may be suspended therefrom as desired.

In the operation of this device the long arm 12 of the lever 10 is swung longitudinally toward the end of the device to which the eye 15 is secured as shown in dotted lines in Fig. 4 and this swinging of said arm 12 will cause the short arm 11 to swing upwardly carrying with it the link 8 which forces outwardly the hook 3 spacing the prongs 7 thereof laterally from the base

plate a sufficient distance to permit the engagement of the prongs 7 with the fabric to which the device is to be applied. These prongs are then passed through the fabric 5 and the lever arm 12 is swung backwardly toward the hook 3 thus moving the link 8 connected with the short arm of said lever downwardly and drawing with it the attaching prongs 7 toward the base plate 2 and 10 into closed position, the pivoted end of said link passing the dead center of the fulcrum of the lever when in this position and thus securely locking the lever and the hook connected with it in closed position, all lateral 15 strain exerted thereon being ineffective for opening the hook which can only be accomplished by swinging the lever arm 12 forwardly as above described.

This device may be employed as an attachment for ladies' chatelaine pins, as a means for securing an emblem or class pin and for any other purpose to which it may be adapted.

While I have described my invention with 25 more or less minuteness as regards details and as being embodied in certain precise forms, I do not desire to be limited thereto unduly any more than is pointed out in the 30 claims. On the contrary, I contemplate all proper changes in form, construction and arrangement, the omission of immaterial elements and substitution of equivalents as circumstances may suggest or render expedient.

35 I claim as my invention:

1. An article attaching device comprising a plate, a head pivotally mounted on said plate and having an inwardly curved penetrating prong, a link pivotally connected 40 with said prong adjacent the base thereof, a bell crank lever fulcrumed in alinement with the pivoted end of said link, the free

end of said link being pivotally connected with one arm of said lever and the free end of the other arm of said lever being beveled 45 transversely to position it flush with the outer edge of said plate when the lever is in closed or operative position, said end being thus disposed in convenient position for actuation.

50

2. An article attaching device comprising a plate, a forked holding member pivoted on said plate and having its arms inwardly curved and the free ends thereof pointed to form penetrating prongs, a link having one 55 end offset in a direction opposite to the curvature of said arms and pivotally mounted between said arms near the base thereof, a bell crank lever fulcrumed on said plate in alinement with the center of 60 said holding member, one arm of said lever being pivotally connected with the free end of said link.

3. An article attaching device comprising a plate having a hollow rear face, a head 65 pivotally mounted on said hollow rear face and having inwardly curved penetrating prongs spaced laterally apart, a link pivotally mounted between said prongs, a bell crank lever fulcrumed in alinement with the 70 pivoted end of said link, the free end of said link being pivotally connected with the short arm of said lever and the free end of the long arm of said lever being offset to position its terminal at the outer edge of 75 said plate in convenient position for actuation.

In testimony whereof I have hereunto set my hand in presence of two subscribing witnesses.

DANA E. HEMPHILL.
